Primary Examiner — Doris Clark(74) *Attorney, Agent, or Firm* — Wood, Herron & Evans, LLP(57) **CLAIM**

The ornamental design for a lawn edging, as shown and described.

DESCRIPTION

FIG. 1 is a perspective view of a lawn edging showing our new design and broken in the center thereof to show indeterminate length;

FIG. 2 is a top plan view thereof;

FIG. 3 is a bottom plan view thereof;

FIG. 4 is a left side elevational view thereof with the right side elevational view thereof being a mirror image;

FIG. 5 is a front elevational view thereof;

FIG. 6 is a rear elevational view thereof; and,

FIG. 7 is a top plan view shown in a "U" configuration.
